Inventor:
Rogers M. Warwick.
Williams Bradbury
McCalib & Pierce Atty.

UNITED STATES PATENT OFFICE.

ROGERS M. WARWICK, OF EASTLAKE, FLORIDA, ASSIGNOR OF ONE-HALF TO DUDLEY W. LESTER, OF WILMETTE, ILLINOIS.

DISPENSING CARD CASE.

Application filed December 15, 1921. Serial No. 522,549.

My invention relates to a pocket case comprising means for dispensing, one at a time, a supply of business or calling cards therein contained.

My invention contemplates the provision of a device of the class mentioned that is of sturdy and compact construction and neat in appearance; but comprises a minimum number of parts that may be cheaply manufactured, that is easy to manipulate, and that is positive in its operation.

Another object of the invention is to provide a device of the class mentioned which comprises a card container that is formed from a single piece of metal tubing.

A further object of the invention is to provide a dispensing card case that may be replenished with cards, from time to time, very easily and in a novel manner.

A still further object of the invention is to provide an improved form of attachment between the so-called sliding ejector and the button by which said ejector is operated.

In the accompanying drawings illustrating a preferred embodiment of my invention:

Figure 1 is a top plan view of the card case, certain parts which are normally concealed being illustrated by dotted lines and a portion of the one-piece container being broken away more clearly to reveal the plate which yieldingly supports the cards dispensed;

Figure 2 is an end elevation looking from the left in Figure 1;

Figure 3 is a longitudinal section taken on the line 3—3 of Figure 1, this figure illustrating a plurality of cards in position to be dispensed one by one in the manner presently to be described;

Figure 4 is a transverse section taken on line 4—4 of Figure 3;

Figure 5 is a view generally similar to Figure 3, but illustrating the device in condition to be loaded with cards;

Figure 6 is a view in perspective of the card supporting plate and its associated spring; and

Figure 7 is a fragmentary sectional view illustrating the details of the connection be-

tween the sliding ejector and its associated operating button.

Similar characters of reference refer to similar parts through the several views. 55

Referring to the drawings, reference numeral 10 indicates a card container or housing of the dispensing card case of my invention. The container is formed in one piece from a length of seamless metal tubing such, for instance, as aluminum tubing, which has been given the cross-section illustrated in Figure 4. The container comprises an imperforate bottom wall 10^a, imperforate side walls 10^b—10^b, and a top wall 10^c. The top wall 10^c is provided with a longitudinal slot 11, the purpose of which will presently appear.

Formed integral with one end (the left end in Figures 3 and 5) of the bottom wall 70 10^a is a lip which is turned upwardly between the adjacent ends of the side walls 10^b—10^b, and constitutes an end wall 12. It will be noted that the height of wall 12 is somewhat less than the vertical distance between the inner surfaces of top and bottom walls 10^c and 10^a, there being a transversely elongated slot or card ejection opening 13 between the upper edge of wall 12 and the adjacent end of top wall 10^c. 80

Referring now to Figures 3 and 5, it will be noted that the right ends of the top and bottom walls 10^c and 10^a extend beyond the adjacent ends of the side walls 10^b—10^b, the projecting portions of the top and bottom walls being shaped to provide aligned channels 14—14 for the reception of the upper and lower edges of a removable end plate 15. 85

I now call attention to the card supporting plate 16. This plate is preferably provided with a pair of longitudinal stiffening ribs 17—17 and a downwardly struck boss 18. Fitting around said boss and bearing against the under surface of said plate 16 is a coiled spring 19^a the spring being preferably attached to the boss by having one of its ends extending through diametrically opposite apertures in the boss, as illustrated in Figures 3, 5, and 6. Special attention is called to the transverse shoulder 19 which is formed on the upper surface of plate 16 by making a transverse slit in the plate and 90 95 100

striking the metal on one side of the slit downwardly. This shoulder co-operates with the sliding ejector in a novel manner when the dispensing card case is empty, and **5** thus ready for reloading.

I shall now describe the sliding ejector. At **20** I have illustrated an elongated plate which lies immediately adjacent to the under surface of top plate **10**, and is adapted at **10** all times to prevent the ingress of dust through slot **11**. The plate **20** is formed of comparatively thin sheet metal and is provided at the end thereof next adjacent the removable closure plate **15** with a downwardly turned lip **21**, which has two functions presently to be described.

At **22** I have illustrated a button which constitutes the means for operating and guiding the plate **20**. Button **22** is preferably formed of a soft alloy, and is provided on its under surface with two spaced bosses **23**—**23**, these bosses extending freely through top wall slot **11**, and having snug sliding fits therein. Forming part of each **25** of the bosses **23** is rivet portion **23^a**. Annular grooves **23^b** are formed in bosses **23** at the bases of the rivets **23^a**. Said grooves **23^b** receive the upwardly projecting portions of the metal of plate **20**, which lie around the **30** counter-sunk openings **24**. Rivet portions **23^a** extend through openings **24** and are there riveted, the lower portions of the rivets lying substantially flush with the under surface of the plate **20**. The herein described attachment of button **22** to plate **20** is extremely effective, and easily accomplished.

Now let us suppose that the card case contains a supply of cards **24**—**24**, as illustrated **40** in Figures **3** and **4**. The cards are urged upwardly against sliding plate **20** by the supporting plate **16** and its associated spring **18**. When a card is to be dispensed, the button **22** is moved toward the removable end **45** plate **15** until the lip **21** engages behind the end of the uppermost card. The button is now moved toward the ejection opening **13** and the uppermost card is partially ejected, through the opening **13**. The partially **50** ejected card may be grasped by the operator or by the person to whom the case is presented. This mode of operation may be repeated so long as any cards remain in the case, one card being dispensed each time the **55** button **22** is moved toward the ejection opening following a movement in the opposite direction, which permits the lip **21** to engage behind the end of the uppermost card.

Now let us assume that the last card has **60** been dispensed, and that the operator, not knowing that his supply of cards is exhausted, attempts to operate the device in the normal manner. When the button is moved toward the removable closure plate **65** **15**, the lip **21** engages the shoulder **19** of

plate **16**. Plate **16** is moved with the button and the ejector until plate **16** engages the closure plate **15**, and thus notifies the operator that the case is empty. The operator now removes end plate **15** and by operating **70** button **22** causes the plate **16** to project partially from the container **10**, as indicated in Figure **5**. The operator now takes a suitable stack of cards, and places same upon the outwardly projecting portion of the plate **75** **16**. Downward pressure upon said portion of the plate **16** causes spring **19^a** to yield, the cards thereupon being moved into proper position, plate **16** being returned to its normal operating position at the same time. The removable end plate **15** is now replaced **80** in its guides **14**—**14** and the card case is again ready for use.

While I have illustrated and described the details of a commercially desirable embodiment of my invention, I appreciate that various changes in the details of the device may be made without departing from the scope of my invention. Hence, I do not limit myself to the arrangement and construction of **85** parts herein shown and described, but wish to claim all equivalent constructions falling within the scope of the appended claims.

What I claim as new and desire to secure by Letters Patent of the United States is: **90**

1. A case adapted to receive a supply of cards and provided at one end with a card ejection opening and at the other end with a card insertion opening, an ejector disposed within the case and operable from the outside thereof, said ejector being capable of rectilinear movement between said openings, a card supporting plate within the case, spring means urging said card supporting plate toward the ejector, said ejector adapted to engage a card lying next adjacent thereto, and means on said card supporting plate adapted to be engaged by the ejector when the supply of cards is exhausted. **100**

2. A case adapted to receive a supply of **105** cards and provided at one end with a card ejection opening and at the other end with a card insertion opening, an elongated slot in one wall of the case, an ejector plate disposed within the case and adapted at all times to close said wall, said ejector plate being capable of rectilinear movement between said openings, means extending through said slot

for operating said ejector plate, a card supporting plate loosely disposed within said **110** case, spring means normally urging the card supporting plate toward said ejector, a lip on said ejector plate adapted to engage the

cards to be dispensed, and means on the supporting plate adapted to be engaged by said **115** lip when the supply of cards is exhausted.

3. A case adapted to receive a supply of **120** cards and provided at one end with a card ejection opening, an elongated slot in one of the walls of said case, an ejector disposed

for operating said ejector plate, a card supporting plate loosely disposed within said case, spring means normally urging the card supporting plate toward said ejector, a lip on said ejector plate adapted to engage the

cards to be dispensed, and means on the supporting plate adapted to be engaged by said **125** lip when the supply of cards is exhausted.

3. A case adapted to receive a supply of **130** cards and provided at one end with a card ejection opening, an elongated slot in one of the walls of said case, an ejector disposed

within the case and adapted normally to close said slot, said ejector consisting of an elongated strip of relatively thin metal, means on the ejector adapted to engage the

5 cards to be dispensed, an operating button movable along the outer surface of the slotted wall of the case, said button being provided with a pair of bosses, which extend

through said slot, each of said bosses comprising a rivet portion which extends 10 through and is riveted in an opening in the ejector.

In witness whereof, I hereunto subscribe my name this 12th day of December, 1921.

ROGERS M. WARWICK.
